UNITED STATES PATENT OFFICE.

HIRAM O. TURNER, OF SHERMAN, TEXAS.

CHURN.

SPECIFICATION forming part of Letters Patent No. 308,018, dated November 11, 1884.

Application filed March 21, 1884. (No model.)

To all whom it may concern:

Be it known that I, HIRAM O. TURNER, a citizen of the United States, residing at Sherman, in the county of Grayson and State of Texas, have invented a new and useful Churn, of which the following is a specification.

My invention relates to improvements in churn-powers in which suitable gearing and frame-work operate in conjunction with a vertically-reciprocating dasher; and the objects of my improvements are, first, to provide for the quick and convenient detaching of the churn from the driving mechanism; and, second, to afford facilities for the proper adjustment of the device to the different sizes of churning, in which—

Figure 1 is a side view of the entire machine; Fig. 2 a back, and Fig. 3 a top, view of the same.

Similar letters refer to similar parts throughout the several views.

The frame-work which carries the mechanism for actuating the churn-dasher consists of two parallel bars, A A', held at a suitable distance apart by blocks B, and resting upon legs designated by C C. The rods D, projecting laterally from the bar A', are forked and bent upward at their outer ends, and by securing them to the side of the building or other structure the frame-work is held in an upright position.

Upon the bar A' is secured a standard, E, which is provided with a guide, F, for the reciprocating dasher-shaft G. This shaft passes loosely through a hole in bar A, and from thence into the churn H, the lower end being provided with dashers I, of the usual style, as shown.

K designates the balance and crank wheel 40 for operating the dasher-shaft, and a a detachable pitman which connects the two together, the said pitman being fitted at one end to a pin upon one side of a spring-clamp, c, which grips the dasher-shaft, and at its remaining end into one of a series of holes formed in a spoke of the crank-wheel. The axis of this wheel is journaled in boxing e, secured upon the bar A, and is provided with a toothed pinion, i, which engages with a driving gear-wheel L. This wheel is provided with a crank-handle for operating the same.

The letter n indicates a dovetailed block, which sets detachably in a dovetailed recess, the object of which is to hold the churn-dasher 55 shaft in place when the churn is in operation.

To remove the power from the churn, the dovetailed block n is removed and the pitman disengaged from the dasher-shaft, when the shaft may be entirely freed from the guide of 60 standard E, leaving the churn free to be either emptied or filled, as the case may be, and then the several parts reconnected for purposes of churning.

Having thus described my invention, what I 65 claim as new, and desire to secure by Letters Patent, is—

The combination of the frame formed of the parallel bars A A', the dasher-shaft G, the dovetailed block n, mechanism, substantially 70 as described, for reciprocating the dasher-shaft, the two legs C C, and the laterally-projecting forked rods D D, as and for the purposes specified.

HIRAM O. TURNER.
